UNITED STATES PATENT OFFICE.

MEYER L. ROBBINS, OF NEW YORK, N. Y.

WATCH-BRACELET.

1,177,274.

Specification of Letters Patent. Patented Mar. 28, 1916.

Original application filed October 29, 1915, Serial No. 58,576. Divided and this application filed February 5, 1916. Serial No. 76,312.

To all whom it may concern:

Be it known that I, MEYER L. ROBBINS, a citizen of the United States, and a resident of the city, county, and State of New York, have invented a certain new and useful Improvement in Watch-Bracelets, of which the following is a specification.

This invention relates to watch bracelets, and especially those of the type known as "convertible," and the object of this invention is to provide a bracelet of this type wherein the watch can readily be detached and used for other purposes such as a brooch watch or chatelaine.

When the ordinary bracelet watch is detached and used for other purposes the link secured to the watch to which the bracelet is attached is readily discernible and it can be seen that a bracelet watch is being used. By the use of my improved end link and means for connecting the same to the watch case, this disadvantage is avoided and the watch can readily be detached from the bracelet and worn in any other manner without it being known that a bracelet watch is being used.

These and other improvements are carried out by my invention, a more particular description of which will appear below.

Referring to the accompanying drawings, annexed hereto and forming part hereof, Figure 1 is a plan view of my improved attaching link showing the method of connection to the watch, a portion of the watch case being shown; Fig. 2 is a perspective view of the locking member of the attaching link; Fig. 3 is a side elevation partly in section of the attaching link; and Fig. 4 is a plan view of the same.

Throughout the various views of the drawings, similar reference characters designate similar parts.

This application is a division of my co-pending application, Ser. No. 58,576, filed October 29th, 1915.

My improved attaching link in which the invention resides consists of an outer member having two trough shaped side members 1, connected at their ends by the cross members 2. The locking member 3, of the attaching link is slidably mounted within the outer member and has two resilient tongues 5 and 6. The lower tongue 6 is slit as at 7 dividing the end of the tongue 6 into two parts 8, each of which parts has an offset

arm 9, the ends of said arms 9 being provided with studs 10 which studs extend toward one another and form jaws to engage the watch case, as will now be described.

The watch case 13 is provided with the usual hinge 12, and formed in the ends of said hinge are recesses 11, into which the studs 10 extend. A collar 14 is slidably mounted on the attaching member and has openings 15 and 16 through which the tongues 5 and 6 pass. The tongue 5 is provided adjacent its free end and on its upper face with a projection 17 and a hooked and serrated outer end 18. A spring 4 extends between the end 2 of the outer member and the rear of the attaching or locking member and tends to hold the attaching member within the outer member as shown in Fig. 1, whereby the front of the outer member bears against the collar 14 and prevents the collar 14 from moving back on the attaching member until the attaching member is pulled forward, as shown in Figs. 3 and 4, against the tension of the spring 4. When in this position the tongue 5 can be pushed down so that the collar 14 can move over the projection 17 and be slid back on the attaching member allowing a spreading of the jaws, as shown in Fig. 2, whereby the attaching link can be readily removed from engagement with the watch bracelet. In case the link inadvertently assumes the position shown in Figs. 3 and 4, as when the links of the bracelet are expanded when placing the same on the arm, the collar 14 is further prevented from slipping back on the locking member by the projection 17.

From the foregoing, it is obvious that my invention is not restricted to the exact embodiment shown herein but is broad enough to cover all structures coming within the scope of the annexed claims.

Having described my invention, what I claim is:

1. A fastening means for watch bracelets and the like, comprising an outer link, a locking member slidable therein, jaws on said locking member for engaging a watch, movable means slidable on said locking member for drawing said jaws toward one another and holding the same into engagement with a watch case, and means on the locking member for holding said movable means into position.

2. A fastening means for watch bracelets

and the like comprising an outer link, a locking member slidably mounted within said outer link, a pair of laterally movable jaws on one end of said locking member, 5 means independent of the outer link movable on the locking member for drawing the jaws together and holding the same in their contracted position in engagement with a watch case, and means for holding said movable means in position.

3. A fastening means for watch bracelets and the like comprising an outer link, a locking member slidably within said outer link having a pair of tongues, a clamp formed 15 on the end of one of said tongues for engaging a watch case, means independent of the outer link embracing both of said tongues and drawing the sides of the clamp together for engaging a watch case and a spring extending between the outer link and the locking member.

4. A fastening means for watch bracelets and the like comprising an outer member, a locking member slidably within said outer member, a spring extending between the outer member and locking member, a pair 25 of resilient tongues on said locking member, the end of one of said tongues having a pair of laterally distensible jaws, a sliding collar mounted on the locking member and embracing both of said tongues and adapted to draw the jaws toward one another where-

by said jaws are held in engagement with a watch case.

5. A fastening means for bracelets and 35 the like comprising a watch case having a pair of openings, a clasp comprising an outer link, a locking member slidably within the outer link having a pair of resilient tongues, one of said tongues being split, 40 dividing the tongue into two arms, studs on said arms for engaging the openings in the watch case, a slideable collar on the catch member for drawing the arms together and retaining the studs in engagement with 45 the openings in the watch case and a projection on one of the tongues of the catch member for engaging the collar.

6. A fastening means for watch bracelets and the like, comprising an outer link, a locking member slidably within the same having a pair of tongues, laterally distensible jaws formed on one of said tongues for engagement with a watch case, a collar slideable on said tongue and embracing the jaws, 55 means for holding the locking member within the outer link, a portion of said outer link bearing against the collar and holding the same against movement whereby a distension or spreading of the jaws is prevented.

Signed in the city, county and State of New York, this 31st day of January, 1916.

MEYER L. ROBBINS.
